UNITED STATES PATENT OFFICE.

AUGUST J. HINZ, OF WOOD LAKE, MINNESOTA.

LOADING MACHINE.

Application filed July 7, 1920. Serial No. 394,439.

To all whom it may concern:

Be it known that I, AUGUST J. HINZ, citizen of the United States, residing at Wood Lake, in the county of Yellow Medicine and 5 State of Minnesota, have invented certain new and useful Improvements in Loading Machines, of which the following is a specification.

This invention relates to improvements 10 in loading machines especially adapted for loading manure though not necessarily restricted to such use.

An important object of this invention is 15 to provide a loading machine having novel means whereby material may be readily and conveniently picked up and supplied to the conveyer which elevates and discharges the same into a wagon.

A further object of this invention is to 20 provide a loading machine having a shovel or pick-up device provided with automatic means whereby the same is dumped upon reaching the limit of its upward movement or upon moving to a point above the conveyer.

The invention forming the subject matter 25 of this application aims also to provide a loading machine having automatic means for stopping the shovel or pick-up device when the same reaches the limit of its upward movement.

A further object of the invention is to 30 provide a loading machine which is simple to operate, and efficient and durable in use.

35 Other objects and advantages of the invention will be apparent during the course of the following description.

In the accompanying drawings, forming 40 a part of this application and in which like numerals are employed to designate like parts throughout the same,

Figure 1 is a side elevation of the improved loading machine,

Figure 2 is a plan view of the same,

45 Figure 3 is a fragmentary side elevation of the machine, the shovel or pick-up device being shown in its dumping position,

Figure 4 is a detail section through a clutch embodied in the invention,

50 Figure 5 is a group perspective of the operating means for the clutch.

In the drawings, wherein for the purpose of illustration is shown a preferred embodiment of the invention, the numeral 10 designates the body of the improved machine

which is mounted upon wheels 11 so that the same may be conveyed from place to place by a tractor or by horse power. Standards 12, 13 and 14, preferably of U-shaped formation are mounted upon the base 10 and 60 form a means for supporting a conveyer 15 in an inclined position. The conveyer 15, which may be of standard construction, comprises the usual frame about which an apron 16 extends. The apron, of course, is endless 65 and is composed of a plurality of strips connected in any well known manner so that the same may pass about the rollers 19 and the ends of the conveyer. As illustrated in Figure 1, an engine 20 is mounted on the 70 base 10 and is provided with a power transmitting wheel 22 having connection with a second wheel 24 through the medium of a belt 25. The wheel 24 which is disposed beneath the conveyer, has connection with the 75 upper roller 19 of the apron by means of sprocket wheels 20' and 21 and by a connecting sprocket chain 23. In this manner the power of the engine is transmitted to the apron 16 so that when the engine is running 80 the apron will be passed over the rollers, though, if desired, a clutch may be interposed between the driving connection of the engine and the apron.

The means employed for dumping the material onto the apron comprises a shovel 30 which is L-shaped in side elevation and which comprises a plurality of spaced parallel forks. The shovel 30 is formed with a pair of forwardly extending spaced parallel 90 arms 32 having elongated slots 33 within which rollers 34 operate. The rollers 34 which operate in the elongated slots 33 have connection with a cross head 35 which, in turn, is connected intermediate its ends to a 95 cable 36 through the medium of a clevis 37 and a pulley 38. The cable 36 is anchored at one end to the U-shaped lifter 39 having its sides horizontally pivoted as indicated at 100 140 to upstanding extensions 41 secured to the lower portion of the elevator. The U-shaped lifter 39, which is movable over the conveyer, is adapted to be elevated for positioning the shovel 30 above the apron so that the material carried by the shovel may be 105 discharged onto the apron. The cable 36 which has connection with the connecting portion of the U-shaped lifter, is wound about a drum 40 rotatably carried by the standard 12 and operated from the engine by 110

a means to be more fully hereinafter described. When the drum 40 is operated in an anti-clockwise direction, as indicated by the arrow in Figure 2, the cable will draw 5 the shovel 30 in the direction of the conveyor and when the shovel reaches the limit of its movement along the ground, the pressure or pull on the cable causes the lifter 39 to be elevated with the result that the shovel 10 is raised.

When the shovel reaches the limit of its upward movement, the sides of the lifter engage a stop element 43 carried by the extension 41 and which serves as a means for 15 limiting the forward movement of the lifter and consequently the shovel.

The cable 36 is guided onto the drum 40 by a pair of pulleys 44 which are carried by a carriage 45. The carriage is, in turn, 20 mounted on a screw threaded bar 46 extending in spaced parallel relation to the drum and in advance of the same. The screw threaded bar 46 is, of course, rotated during the operation of the machine so that 25 the carriage 45 is moved transversely of the apparatus for properly feeding the cable 36 onto the drum.

The means employed for transmitting a 30 rotary motion to the drum 40 comprises a combined clutch and sprocket wheel 50 having an annular series of teeth 51 which are engaged by a sprocket chain 52 having connection with the power transmitting wheel 24 through the medium of a small sprocket 35 wheel 53. As illustrated in detail in Figure 4, the clutch section 50 is rotatably mounted on a shaft 55 of the drum 40 and is formed with a socket which receives the male section 56 of the clutch. The section 40 56 comprises a hub 57 to which a plurality of contact members 58 are connected. The hub 57 of the male section 56 is slidably and non-rotatably arranged on the shaft 55, so that when the clutch section 56 is 45 moved into engagement with the section 50 a driving connection will be provided between the sprocket chain 52 and the drum 40. The male section 56 is formed with an annular collar 60 within which the arms 50 of a dog 61 are arranged. The dog 61 has a pivotal connection with a vertically arranged lever 62 adapted to be operated for moving the male section 56 along the shaft 55 whereby the driving connection between 55 the sprocket chain 52 and the drum 40 may be broken if desired. The upper end portion of the lever 62 is suspended from a laterally projecting bracket 63 carried by one side of the standard 12. As illustrated 60 in Figure 5, the lower portion of the lever 62 is formed with an L-shaped attaching arm 63' having an elongated slot 64 which slidably receives a bolt 65 carried by the lower portion of the standard 12. In this 65 manner, the lower portion of the lever is

not allowed to sway laterally or partake of unnecessary movement during the operation of the machine.

As the lifter 39 is elevated, the same engages the longitudinally movable releasing 70 rod 68 carried by brackets 69 and 70 secured to the standard 12. The longitudinally movable rod is square in cross section so that the same will not be allowed to rotate while partaking of a longitudinal 75 movement. One end portion of the tripping or releasing rod 68 is forked as indicated at 71 and is disposed in the path of travel of the lifter so that as the lifter is elevated the rod will be moved rearwardly. 80 The longitudinal movement thus imparted to the releasing rod 68 forces the wedge shaped head 72 of the same between the adjacent side of the standard 12 and the lower portion of the lever 62, so that the lever is 85 caused to partake of a pivotal movement. This pivotal movement thus imparted to the lever causes the male section 56 of the clutch to be released from the section 50 so that the driving connection between the 90 engine and the drum is broken when the lifter reaches the limit of its upward movement.

A beam 75 extends longitudinally of the machine at a point spaced above the conveyor and is provided with a pulley 76 over which a cable 77 is passed. The cable 77 has its ends wrapped in opposite directions about a drum 78 so that when the drum rotates one end portion of the cable will be wound 100 upon the drum and the other end portion of the cable will be released from the drum. The end portions of the cable are guided onto the drum by pulleys 80 which are mounted upon carriages 82 which correspond 105 in construction and purpose to the carriages 45. The carriages 82 are mounted on a screw threaded bar 83 which serves as a means of seating the carriages as the pulleys 110 rotate.

As illustrated in Figure 2, the drum 78 is provided at one end with a pulley 84 which is connected to a pulley 85, operated by the motor 20, through the medium of a belt 86. The rotation thus imparted to the 115 drum 78 is imparted to the screw threaded bar by means of a sprocket chain 87 which passes over sprocket wheels mounted on the shaft of the drum 78 and on the screw threaded bar 83. The carriages 82 are prevented from rotating by reason of the fact that the same have sliding contact with a cross member 88 carried by the standard 13.

The cable 77 carries a flexible element 90 which is provided at its lower end with a hook 91 adapted for engaging the shovel 30. As the cable 77 partakes of a movement in a direction indicated by the arrow in Figure 1, the cable 90 partakes of a like movement with the result that the shovel is returned 130

to its downward position against the tension of a pair of contractile coil springs 93 which are connected to the lifter 39 and to the extensions 41. When the shovel is returned 5 to the ground, the movement of the depending cable 90 may be stopped by operating a clutch 94 connected with the drum 78. The clutch 94 may be operated by means of a depending lever 95.

10 In order to allow the shovel 30 to be adjusted for picking up an entire pile of material, the beam 75 is pivoted to the standard 14 as indicated at 97 and has its forward portion supported by a plurality of standards 98.

15 The apparatus is positioned with the lower end of the conveyer near the material so that as the shovel is operated, the material will be discharged onto the conveyer. Of course, a wagon or other vehicle is arranged beneath the discharge end of the conveyor so that the material will be collected upon being discharged into the same.

20 When the engine is started, the power will be transmitted to the several drums and to the rollers so that all will operate practically simultaneously. The rotation of the drum 40 results in movement of the shovel through the material and in the subsequent 25 elevation of the lifter 39. The elevation of the lifter 39 results in dumping of the material from the shovel onto the conveyer with the result that the material is elevated and dumped into the wagon. When the 30 lifter 39 reaches the limit of its upward movement, the same engages the longitudinally movable tripping device so that the driving connection between the engine and the drum 40 is automatically released, stopping the pull on the lifter. As the cable 77 35 is brought into operation, the hook 91 of the depending cable 90 will engage the shovel and return the same to the position illustrated in Figure 1. The motor is, of course, 40 provided with means whereby the direction of rotation of the drum may be reversed.

45 Attention is invited to the fact that when the shovel reaches the limit of its upward movement the cross-head 35 engages a pair of arms 100 so that the shovel may be manually tilted or dumped for discharging the contents of the same. When the shovel is tilted the rollers 34 move rearwardly within the slots 33.

50 With reference to the foregoing description it will be observed that a material loader constructed in accordance with this invention will efficiently load the material with a minimum of effort and inconvenience 55 on the part of the operator.

60 It is to be understood that the form of the invention herewith shown and described is to be taken as a preferred example of the same and such minor changes in arrangement and construction of parts may be made

as will remain within the spirit of the invention and the scope of what is claimed.

Having thus described the invention, what is claimed as new is:

1. A loader comprising a portable frame, 70 an inclined conveyer mounted upon the frame, a motor upon the frame, a lifter pivotally mounted at the lower end of the conveyer, a shovel for dumping material onto the conveyer, a drum carried by said frame 75 above the conveyer, operative connections between the motor and the conveyer and between the motor and the drum, and a cable having one end secured to the lifter and its opposite end wound on the drum and its intermediate portion operatively connected with the shovel adjacent the lifter whereby when the cable is wound on the drum the shovel will be drawn to the lifter and the lifter and shovel then raised. 80

2. A loader comprising a portable frame, 85 an inclined conveyer mounted upon the frame, means for operating said conveyer, a shovel arranged to deposit material on the conveyer, a drum carried by the frame above the conveyer, means for operating the drum, a lifter pivotally mounted at the lower end of the conveyer, a cable arranged to wind upon the drum and secured at one end to the lifter a pulley on the shovel and around which the intermediate portion of the cable is trained, and means to operate the drum whereby to draw the shovel to the lifter and then raise the lifter and the shovel. 90

3. A loader comprising a portable frame, 95 an inclined conveyer carried by the frame, a drum mounted on the frame above the conveyer, a shovel, a cable wound about the drum and connected with the shovel, means for operating the drum to raise the shovel, and means actuated by the shovel for releasing the drum from said operating means as the shovel is raised. 100

4. A loader comprising a portable frame, 110 an inclined conveyer carried by the frame, a drum mounted on the frame above the conveyer, a cable wound about the drum, a shovel connected with the cable, a lifter pivotally mounted at the lower end of the conveyer and having the end of the cable 115 secured thereto, a motor, operative connections between the motor and the drum including a clutch and a lever controlling the clutch, and a releasing rod having one end 120 arranged to bear upon the clutch-controlling lever and its opposite end arranged to be actuated by the lifter whereby to release the clutch-controlling lever when the lifter is raised. 125

5. A loader comprising a frame, an inclined conveyer mounted on the frame, a motor upon the frame, a shovel supported from the lower end of the conveyer, a cable having connection with the shovel, a drum 130

mounted upon the conveyer and having the cable wound thereon, means whereby the motor will operate the conveyer and the drum, a second drum mounted on the frame in advance of the first drum, a second cable having its end portions wound in opposite directions upon the second drum and extending rearwardly over and beyond the first drum, and a suspending device carried by 10 said second cable and adapted to engage the rear end of the shovel.

6. A loader comprising a frame, a conveyer mounted therein, a shovel disposed adjacent the receiving end of the conveyer, a lifter pivoted at the receiving end of the conveyer, a yieldable connection between the free end of the lifter and the frame, a drum on the frame above the conveyer, a cable secured at one end to the drum and at its opposite end to the free end of the lifter and having its intermediate portion engaged

with the shovel whereby winding of the cable upon the drum will raise the shovel and the lifter, and means on the frame to limit the raising movement of the lifter. 25

7. A loader comprising a frame, a conveyer mounted therein, a shovel disposed adjacent the receiving end of the conveyer, a lifter pivoted at the receiving end of the conveyer, a cross head slidably mounted on the shovel, a drum on the frame above the conveyer, a cable secured at one end to the drum and at the opposite end to the lifter and having its intermediate portion operatively engaged with said cross-head whereby when the cable is wound on the drum the shovel will be drawn to the lifter and the lifter and shovel raised, and arms on the lifter to engage the crosshead to effect dumping of the shovel. 30

In testimony whereof I affix my signature. 35

AUGUST J. HINZ. 40
